LAMP SWITCH OPERATOR

Benjamin Schoenberg, Corona, Long Island,
N. Y., assignor to Eagle Electric Mfg. Co., Inc.,
Brooklyn, N. Y., a corporation of New York

Application August 13, 1938, Serial No. 224,813

4 Claims. (Cl. 240—123)

This invention relates to operators for attachment to ceiling canopies that enclose interiorly mounted electrical sockets operable by sidewardly extending pull-chains, usually formed of ball and socket links.

6 Among the features of the invention are a bracket so formed that it firmly engages the lower rim of the canopy and is secured thereto detachably by a screw, a lever being pivotally mounted on the bracket so that it can be rocked 10 away from and towards the canopy, and the lever may have two arms disposed at an acute angle with reference to each other, and be formed angularly in cross-section, and a notch may be formed in the lever, or a plurality of slots or 15 notches formed in the side of the lever, the slots or notches being of such size as to permit the insertion of a pull-chain therein and being so positioned that they securely hold the pull-chain against escape when the lever is rocked outwardly or inwardly, and these slots also permit fastening the lever to the pull-chain in a number of different positions along the length of the chain so that the lever may be adjusted with reference to the pull-chain which operates the electrical switch. Another feature of the invention 20 is the provision of a stop limiting the motion of the lever toward the canopy.

It is the principal object of the invention that the lever normally is in the upper position nearest the canopy where it is held by the tension of the electrical switch spring, but a downward pull on a string suspended from the lever operates the switch. To minimize tension on the switch spring the lever itself may be made of 25 metal angular in cross-section, and the pull-cord of light material. When the pull-cord is released the spring of the electrical switch automatically returns the lever to its normal or inoperative position.

40 Other objects will appear as the description proceeds.

Reference is made to the drawing, in which Figure 1 is a side view part in section.

Figure 2 is a front view, partly broken away.

45 Figure 3 is a side view of a modification, part in section.

Figure 4 is a front view of Figure 3, part broken away.

50 Figure 5 is a side view of another modification, part in section.

Figure 6 is a front view of Figure 5, part broken away.

55 Figure 7 is a side view of another modification, part in section.

Figure 8 is a front view of Figure 7, part broken away.

Referring to the drawing and especially to Figs. 1 and 2 a ceiling canopy 10 of the usual construction is provided with a ball and socket pull-chain 11 extending through a nipple or stud on the side of the canopy. The improved device in one form comprises a bracket which has a downward extension 15 curved inwardly at the bottom at 13 to engage linearly the bottom or rim of the canopy 10 and an upward extension 14 adapted to engage the inside of the canopy 10. The outer face of the dependent part 15 is provided with a threaded hole adapted to receive a screw 16, which, when turned in, engages the outside of the canopy 10 and securely clamps the bracket on the lower rim of the canopy. The bracket has an upward extension 17 at right angles to the part 13 and is provided with a pivot hole in which a pivot pin 18 is secured. The pivot pin 18 also pivotally supports the operating lever which has a long outer arm 19 at the outer end of which is a hole 20 through which a pull cord 45 may be passed and knotted to be secured against pulling through the hole. The lever 19 is formed angularly in cross section to lighten it and to enhance its rigidity and strength and has an arm 21 disposed in the same plane as the arm 19 and at an acute angle with reference thereto. The arm 21 has a plurality of outwardly and downwardly inclined notches 22 into which the ball and socket pull chain can be inserted at different positions along the chain so that the lever arm 21 may be secured to the pull chain to hold the lever in a plurality of predetermined positions with reference to the pull chain 11. The operation is now obvious; a downward motion on the long arm 19 of the lever causes the shorter arm 21 of the lever to rock away from the canopy 10 and to operate the switch which is connected with the pull chain 11. The operative position is shown in dotted lines for all modifications. As is well known in the art, these switches contain a spring which automatically returns the pull chain to the inoperative position and simultaneously lifts the lever 19 to the inoperative position upon releasing the cord that is attached to the end of the long arm of the lever.

A modified form is shown in Figures 3 and 4. The bracket has a flat depending piece 55, a bottom piece 56, and an inside piece 57 for engaging the rim of the canopy 10 to which it is fastened by the screw 16. The lever has a long arm 54 and a short arm 62 which latter normally engages a stop 59 on an arm 58 rising on 55

the bracket. The lever fulcrum 60 turns on a pin 61 which is horizontally mounted in the bracket. The arm 62 is obtuse-angled in cross-section and has an angled lengthwise extension 52 in which are formed a plurality of downwardly inclined slots 53, which permit a greater variety of adjustments of the pull chain.

Another modified form is shown in Figs. 5 and 6 adapted for a canopy 30. In this case 10 the electrical switch is provided with a ball-and-socket pull chain 11 which passes through the side near the bottom of the canopy 30. In this modification the bracket 31 has an opening 36 in its upper extension 31 which is adapted to fit 15 around the opening in the nipple of canopy 30 through which the pull chain passes. A locking nut 35 is placed on a threaded apertured stud or nipple outside the pull chain aperture 36 and when tightened engages the bracket 31 and presses it tightly against the canopy 30. The bracket has a downwardly and outwardly 20 curved portion 32 which terminates in an extension 34 at right angles to the body of the bracket 31. This extension is provided with an aperture 25 for supporting therein a pivot pin 37 which mounts the lever by means of an aperture near the apex of the angle between the long arm 19 of the lever and the short arm 21. This lever is angled in cross-section and at the outer end 30 of the long arm is provided with a hole 20 through which a pull cord 45 may be passed for operating the lever and the short arm 21 is provided with downwardly and outwardly inclined notches, or slots 22 for receiving and 35 securing the ball and socket chain which operates the electrical switch. These notches, or slots, are so constructed that they receive the connecting parts between the balls of the chain so that by locking the chain between adjacent balls it 40 is secure against escape in either direction but the position of the chain linearly may be varied and by locking the chain in one slot instead of in another slot the position of the chain also may be likewise varied.

Another modified form is shown in Figures 7 and 8. A bracket 70 engages the outside of the canopy 30, and has a hole 71 surrounding the nipple or stud on the side of the canopy through 45 which the pull chain 11 passes. A nut 72 locks the bracket 70 against the canopy 30. The bracket 70 has at the bottom an outwardly and upwardly extending arm 73 bifurcated at the ends 74 to support a pivot pin 75. The long arm 77 of the lever supports the pull cord 45 at the 50 outer end and the short arm 76 is formed at the upper end with a notch 78 having a narrow top central opening and a circular enlargement below but smaller than the balls of the chain 11. As the chain is pushed down the link of the chain 55 passes through the narrow top aperture and lies in the enlarged bottom of the notch 78, so that it is locked against movement in either direction.

Modifications may be made, parts may be used without others, and parts may be substituted for others, all within the spirit and scope of the invention.

I claim:

1. A pull-chain switch operator comprising in combination, a bracket having a U-shaped lower

end adapted to engage the cylindrical skirt of a canopy and the rim thereof, a screw threaded thru the outer wall of the U and engageable with the outer wall of the skirt to press the inner part of the U firmly against the inner wall of the 5 skirt, a vertical extension from the outer part of the U, an acute angled lever pivotally mounted transversely on the vertical extension with one arm of the lever extending outward and another arm extending vertically upward, said vertical 10 arm having a lateral extension with a downwardly inclined slot therein for engaging a pull chain, and a stop for limiting the movement of the lever toward the canopy.

2. A pull-chain switch operator comprising in 15 combination, a bracket having a U-shaped lower end adapted to engage the cylindrical skirt of a canopy and the rim thereof, a screw threaded thru the outer wall of the U and engageable with the outer wall of the skirt to press the inner part 20 of the U firmly against the inner wall of the skirt, a vertical extension from the outer part of the U, an acute angled lever pivotally mounted transversely on the vertical extension with one arm of the lever extending outward and the other 25 arm extending vertically upward, said vertical arm having a lateral extension with a downwardly inclined slot therein for engaging a pull chain, and a pull cord attached to the outer arm of the lever.

3. A pull-chain switch operator comprising in combination, a bracket having a U-shaped lower end adapted to engage the cylindrical skirt of a canopy and the rim thereof, a screw threaded thru the outer wall of the U and engageable with the outer wall of the skirt to press the inner part 35 of the U firmly against the inner wall of the skirt, a vertical extension from the outer part of the U, an acute angled lever pivotally mounted transversely on the vertical extension with one 40 arm of the lever extending outward and the other arm extending vertically upward, said vertical arm having a lateral extension inclined outwardly away from the canopy with a plurality of downwardly inclined slots therein for engaging 45 a pull chain, and a pull cord attached to the outward arm of the lever.

4. A pull-chain switch operator comprising in combination, a bracket formed of flat metal and having a U-shaped lower end adapted to engage 50 opposite sides of the cylindrical skirt of a canopy and the lower rim thereof, a set-screw threaded thru the outer wall of the U and engageable with the outer wall of the skirt to press the inner part of the U firmly against the inner wall of the 55 skirt to secure it thereon, a vertical extension from the outer wall of the U twisted into a plane at right angles to the outer wall of the U, an acute angled lever having a flat apex, a pivot pin extending through said vertical extension and said flat apex and holding said extension and said lever in pivotal engagement, one arm of the lever extending vertically upward, said vertical arm having a lateral extension and a downwardly inclined slot therein for engaging a downwardly 60 and outwardly extending pull-chain, the other arm of said lever also having a lateral extension, and a pull-cord on said last-mentioned arm.

BENJAMIN SCHOENBERG.
